(57) **CLAIM**

The ornamental design for a cooler and warmer box as shown and described.

DESCRIPTION

FIG. 1 is a front, left and top perspective view of a cooler and warmer box showing our new design;

FIG. 2 is a rear, right and top perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof;

FIG. 8 is a right side elevational view thereof; and,

FIG. 9 is a front, left and top perspective view of the cooler and warmer box showing the handle in an upright position. The broken lines in the drawings illustrate portions of the cooler and warmer box which form no part of the claimed design.

1 Claim, 9 Drawing Sheets
